United States Patent Office.

JEHYLEMAN SHAW, OF BRIDGEPORT, CONNECTICUT.

Letters Patent No. 81,417, dated August 25, 1868.

IMPROVEMENT IN PUMPS.

The Schedule referred to in these Letters Patent and making part of the same.

TO ALL WHOM IT MAY CONCERN:

Be it known that I, JEHYLEMAN SHAW, of Bridgeport, in the county of Fairfield, and State of Connecticut, have invented a new and improved Pump; and I do hereby declare that the following is a full, clear, and exact description thereof, which will enable those skilled in the art to make and use the same, reference being had to the accompanying drawings, forming part of this specification.

This invention consists in placing two ordinary lift-pumps within a cylinder, provided at its lower end with a holding-valve, the piston-rods of the two pumps being connected by cords or chains passing over a pulley, and all arranged in such a manner that the device is made to operate as a force-pump, and elevate water or other fluid to any desired height, according to the amount of power applied to operate it.

In the accompanying sheet of drawings—

Figure 1 is a vertical central section of my invention taken in the line $z z$, fig. 2.

Figure 2, a horizontal section of the same taken in the line $y y$, fig. 1.

Similar letters of reference indicate corresponding parts.

A represents an external case, which may be of cylindrical form, covered at the top, as shown at a , and provided at its lower end with a suction-pipe, B, over the top of which a holding or retaining-valve, C, is placed, as shown clearly in fig. 1.

This external case may be formed of two or more parts, connected by screw-joints, and divided by a partition, a^x , and within this cylinder there are fitted and firmly secured two ordinary lifting-pumps, $C \times C^x$, provided respectively with the ordinary valve-pistons $b b'$, and piston-rods $c c'$.

At the bottom of each pump-cylinder the usual holding-valves, $d d'$, are placed.

The piston-rods of the two pumps are connected by two cords or chains, $e e'$, one of which, e' , has its ends attached to the lower ends of the piston-rods, and is fitted in a groove in a fixed pulley, D, over which it works, the other cord or chain, e , having its ends attached to the piston-rods considerably above the pistons, and working in another groove in the pulley D, under which it passes.

This will be fully understood by referring to fig. 1, and it will be seen that by thus constructing the two pumps, they are made to operate simultaneously in reverse directions, one rising as the other descends, and vice versa.

The piston-rod c is tubular, and communicates with the interior of its piston, b , and this piston-rod has an extension-pipe, E, attached, which passes up through the top, a , of the case, and has the power attached to it by which the pump is operated.

The piston-rod c , a short distance above the piston, has openings, f , made in it.

The operation is as follows:

A reciprocating motion is given the extension-pipe E, and the pistons $b b'$ of the two pumps will move simultaneously in opposite directions, and water be drawn up into the cylinder A, and through the two pumps, and discharged into the upper compartment of A, which forms an air-chamber, the water being discharged from the upper end of the extension-pipe E.

The operation of the two pumps, in connection with the air-chamber, insures a continuous discharge of water from E, the water passing into E through the openings f .

It will be seen, of course, that the water cannot rise in the upper compartment of the case A beyond a certain extent, as the air which is contained therein will prevent it.

By this arrangement, a very simple and efficient force-pump is obtained, and one which will operate perfectly on a large scale with but a moderate expenditure of power, as there is but a small amount of friction to overcome in the working parts.

I claim as new, and desire to secure by Letters Patent—

The two lifting-pumps $C \times C^x$, fitted within the external case A, provided with a valve, C, at its bottom, and all constructed and arranged to operate in the manner substantially as and for the purpose herein set forth.
